UNITED STATES PATENT OFFICE.

HARRY F. DRAKE, OF MILWAUKEE, WISCONSIN.

CLOTHESLINE CLAMP.

Application filed September 24, 1926. Serial No. 137,490.

The invention relates to clothes line clamps.

An object of the invention is to provide a simple, durable and inexpensive clothes line clamp adapted for mounting on a pole, wall 5 or other support and capable of securing a clothes line at any desired degree of tension.

Another object of the invention is to provide a clothes line clamp of this character including a movable clamping member which can be 10 manipulated by the clothes line into either clamping or releasing position.

The invention further consists in the several features hereinafter set forth and more particularly defined by the annexed claims.

15 In the accompanying drawings, Fig. 1 is a side elevation of a clothes line clamp embodying the invention, showing the manner of securing a clothes line thereon;

Fig. 2 is a front elevation of the clothes 20 line clamp;

Fig. 3 is a plan view thereof; and

Fig. 4 is a side elevation similar to Fig. 1 but showing a different manner of securing the clothes line.

25 In these drawings, 10 designates a bracket having a base flange 11 provided with apertures 12 for the reception of the screws 13, by which the bracket can be secured to a pole, wall or other support 14. The bracket 10

30 projects outwardly from the support and is provided at its outer end with a laterally projecting flange 15, which is preferably inclined forwardly and downwardly and which forms a line clamping jaw. The flange 15 is 35 provided at its upper and lower edges with notches 16 and 17, respectively, adapted to receive a clothes line 18.

A clamping dog 19 is pivotally mounted on the bracket 10 by a bolt 20 passing through 40 the bracket near the base flange 11. The dog 19 projects forwardly from its pivotal mounting and has a laterally projecting flange or jaw 21 at its forward portion spaced a short distance from the laterally projecting flange 15 from the bracket 10 and provided with transverse grooves 22 to form a corrugated line clamping surface. The pivoted dog 19 is capable of falling downwardly a short distance away from the clamping position shown 45 in Fig. 1 and, in such lowermost position it is limited by the abutment of its rear edge 23 with the base flange 11 of the bracket.

The clothes line 18 which is supported at a 50 distant point is first introduced into the upper notch 16 from which the line is suspended behind the flange 15. The line may be placed

in this position by tossing it single-handedly into the notch. The line is then given the desired tension by pulling downwardly on the depending portion, which latter is thereupon deflected rearwardly, as indicated in dotted lines, to engage the lower edge of the clamping face of the dog 19, the dog being at this time in its lowermost position. When the clothes line is eased while still holding it in the dotted line position of Fig. 1, the line moves upwardly which carries the dog upwardly and causes the latter to wedge the line tightly between it and the forward flange 15 of the bracket 10, as seen in Fig. 1. As additional load is placed on the span of line 18 the clamping engagement will be tightened. When it is desired to release the line, the depending portion of the line behind the flange 15 is pulled downwardly, thus releasing the 75 dog 19 which falls to its lowermost position. The line 18 may then be readily removed from the bracket by tossing it single-handedly in an upward and lateral direction. In case increased tension is to be placed on the line 80 without removing it from the bracket, the depending portion of the line is first pulled to produce the desired tension and is then deflected rearwardly to engage the dog, which will be lifted to clamping position as the 85 line is released from the hand.

The inclination of the forward flange 15 of the bracket serves to render more convenient the deflection of the line to dog-actuating position, as the required rearward deflection of the depending portion of the line is thus reduced. The pivotal member 20 for the dog 19 is so placed with respect to the inclined flange 15 that the path of movement of the clamping flange 21 will accommodate 95 various sizes of lines without requiring an excessive amount of travel and without interfering with the line actuation of the dog.

When it is desired to have the same clothes line form two divergent spans anchored on the same bracket the line is preferably supported in the manner indicated in Fig. 4, where an intermediate bight of the line is passed about the clamping flange 21 to engage its rear face and the two spans pass outwardly 100 through the notch 16. In the case of a single line terminating at the bracket the line may be wrapped about the dog as suggested in Fig. 4 with the end portion hanging in front of the flange 15, to prevent accidental dislodgment 110 of the line; or, if desired, the lower notch 17 may be used to receive the end portion of the

line which may be wound several times about the flange 15 in clockwise direction. The two divergent spans of line 18 anchored on the same bracket as shown in Fig. 4 both serve to retain the dog in line-clamping engagement, the lower span of line holding the dog elevated in the same manner indicated in Fig. 1, while the subsequently strung upper span performs the same function by the upward pull on the bight of line surrounding the end flange of the dog.

It will be seen that by means of the device of this invention, a clothes line may be securely clamped in a simple manner by single-handed manipulation and that the tension on the line can be readily adjusted to suit conditions.

What I claim as new and desire to secure by Letters Patent is:

20 1. A line clamp, comprising a bracket having a base flange adapted to be secured to a support and having a laterally projecting forward portion forming a line-clamping surface at its rear face, and a dog pivotally 25 mounted on said bracket adjacent said base flange and having a forward clamping face co-operating with said laterally projecting portion to clamp a line therebetween on the upward movement of said dog, said dog having a part engageable with said base flange for 30 limiting its downward movement and permitting said line to lift said dog into clamping position.

25 2. A line clamp comprising a bracket adapted to be secured to a support and having a line-receiving surface, a clamping member pivotally mounted on said bracket and having a clamping portion upwardly movable from a free gravity-determined position to a 35 clamping position adjacent said line-receiving surface, and a line including a span having its depending end portion interposed between said line-receiving surface and clamping portion of said clamping member, the depending portion of said line being engageable with said clamping member for permitting line tension to lift said member into clamping position and said clamping member being releasable to said free position by a 40 downward pull on said depending portion of the line.

3. A line clamp comprising a bracket having a line-receiving jaw, and a pivotally mounted dog having a clamping jaw co-operating with said bracket jaw for clamping a line between said jaws, said dog being movable upwardly into line-clamping position and downwardly to a free position and being movable to either of said positions by engagement and movement of the line with said dog.

4. The combination of a bracket having a line-receiving jaw, a pivotally mounted dog

having a clamping jaw behind said bracket and co-operating therewith to form a line-receiving space between said jaws, and a line having the end portion of one span passed downwardly into said line-receiving space and engageable with the clamping jaw of said dog while in tensioned position for lifting said dog into clamping position upon the limited release of said tension, and said end portion of the span of line being passed upwardly to form a bight embracing the clamping jaw of said dog and extending from above 75 said jaw to form a second span of line.

5. A line clamp, comprising a bracket adapted to be secured to a support and having a line-receiving jaw, a clamping member pivotally mounted on said bracket laterally of said bracket jaw and having a clamping jaw co-operating with said bracket jaw to clamp a line between said jaws on the upward movement of said clamping member, and means for limiting the downward movement of said clamping member away from said bracket jaw to form a line-receiving space somewhat wider than said line and permitting the line to be inserted in said space for lifting said clamping member to its line-clamping position.

6. A line clamp, comprising a bracket adapted to be secured to a support and having a line-clamping jaw and an upwardly opening line-receiving recess above said jaw, and a clamping member pivotally mounted on said bracket and having a clamping jaw adapted to co-operate with said bracket jaw for clamping a line between said jaws, said recess being adapted to receive the end of a tensioned span of line which depends from behind said recess between said clamping jaws, and said clamping member being movable upwardly to line-clamping position and downwardly to a free position and being movable to either of said positions by engagement and movement of the line with said clamping member.

7. A line clamp, comprising a bracket adapted to be secured to a support and having a line-receiving jaw, and a clamping member pivotally mounted on said bracket and having a clamping jaw adjacent said bracket jaw to receive between them from above a tensioned span of line, said clamping member being normally urged out of co-operative relation with said bracket jaw in the absence of a line but being movable toward said bracket jaw under the influence of line tension for clamping a line therebetween and being releasable to free position by movement of the portion of said line depending from said jaws in a direction opposite to the clamping movement of said clamping member.

In testimony whereof I affix my signature.

HARRY F. DRAKE,
